DE WITT T. MOATS

ATTACHING MEANS

Filed Dec. 26, 1924

FIG. 1.

FIG. 2.

FIG. 3.

Inventor:

D. T. MOATS

By *Monroe Miller*
Attorney

UNITED STATES PATENT OFFICE.

DE WITT TALMADGE MOATS, OF INDIANAPOLIS, INDIANA.

ATTACHING MEANS.

Application filed December 26, 1924. Serial No. 758,224.

To all whom it may concern:

Be it known that I, DE WITT T. MOATS, a citizen of the United States, residing at Indianapolis, in the county of Marion and 60
5 State of Indiana, have invented certain new and useful Improvements in Attaching Means, of which the following is a specification, reference being had therein to the accompanying drawing.

10 The present invention relates to means for attaching together plates and other objects, for example, for attaching the name plate of an automobile to the radiator shell, and aims to provide a novel and improved 65
15 button or device to be secured to or carried by one object or plate to enter an opening or hole in another object or plate for securely fastening said objects or plates together.

A further object of the invention is the 70
20 provision of an attaching button or device of the kind indicated which has a double gripping action to provide for a secure connection and to provide for other advantages as hereinafter more fully set forth.

25 A further object is the provision of such a button or device made from sheet metal in a novel manner to accomplish several advantages.

With the foregoing and other objects in 75
30 view, which will be apparent as the description proceeds, the invention resides in the construction and arrangement of parts, as hereinafter described and claimed, it being understood that changes can be made with- 80
35 in the scope of what is claimed, without departing from the spirit of the invention.

The invention is illustrated in the accompanying drawing, wherein—

40 Figure 1 is an edge view of the attaching button or device carried by a name plate in a position to enter a hole provided for said button in a radiator shell, the name plate being shown in edge view and the shell in section.

45 Fig. 2 is a diametrical section of the button showing it in position for securing the name plate to the shell.

50 Fig. 3 is a rear view of the parts assembled, a portion of the button being broken away.

As illustrated in the drawing the attaching button or device is employed for securing a name plate 7 of an automobile to the shell 8 of the radiator, although it will be 100
55 understood that the device can be used for attaching together other parts or objects

for which the device is suitable. The shell or object 8 has an opening or hole 9 of circular form, surrounded by a cylindrical in-turned flange 10.

The button or device 11 is carried by the name plate 7 or other object to enter the opening 9 and obtain a gripping hold on the flange 10 or periphery of the opening, for securing the plate or object 7 to the 105
shell, plate or object 8.

The button 11 is composed of two parts or disks of thin resilient sheet metal. One disk or member, indicated at 12, is concavo-convex, with its concaved side disposed toward 70
70 or facing the plate 7, and the other disk or member is disposed between the member 12 and plate 7 and is formed between its edge and center with a frusto-conical portion 13 and the annular abutment 14 at the smaller 75
75 end of said portion 13 against which abutment the member 12 seats. The member which has the portion 13 has an eyelet portion 15 engaging through a central aperture in the member 12 and clinched around the 80
80 edge of said aperture for securing the member 12 against the abutment 14 and providing a central aperture 16 in the abutment opening into the portion 13. The deformed member has a flat annular attaching portion 85
85 17 surrounding the larger end of the frusto-conical portion 13 to be soldered or otherwise secured to the back surface of the plate or object 7. A flared portion 18 extends from the portion 17 and surrounds the portion 13, but is spaced from the member 12. From the portion 18 extends an annular gripping flange 19 which extends substantially parallel with the edge portion 20 of 90
90 the member 12. The flange 19 is concavo-convex similar to the member 12, so that the edge portions of both disks or members are turned toward the plate or object 7. The central portions of the disks being secured together and to the plate 7 will be rigid, 95
95 while the edge or marginal portions thereof are free to bend, said edge portions being spaced apart and being located at different distances from the plate 7. The central offset portion 13 of the corresponding disk 100
100 provides means for the attachment of the other disk so that by using the two disks a double gripping action is provided when the button enters the opening 9.

The two disks or gripping members are 110
110 slightly larger in diameter than the opening 9, so that when the button is shoved or

forced into the opening, the edges of the disks will be sprung toward the plate or object 7, thereby causing the edges of the disks to grip the flange 10 or wall of the opening 9. This will securely fasten the plate 7 to the shell 8, and the removal of the plate 7 from the shell 8 is resisted inasmuch as the disks have a tendency to spring away from the plate 7 and bite or grip the flange 10 to prevent the parts from separating. The double gripping edges are of advantage, not only to obtain a double gripping action, but to obtain other advantages also. Thus, the disk 12 will have a freer flexing action than the flange 19, as will be apparent, thereby providing two different degrees of gripping action between the button and the flange 10. Furthermore, the disk 12 can be started into the opening 9, thereby centering the plate 7 with reference to the opening 9, before the flange 19 enters said opening, and the name plate can then be turned around its axis to position said plate properly before the second gripping disk is pushed into the opening 9. It will be apparent that the eyelet portion 15 provides a swivel connection between the two disks. Furthermore, by having the two gripping edges the plate 7 can be guided into place more conveniently without the plate being tilted at an angle with the shell or plate 8, and the plate 7 is therefore guided straight into position against the shell or plate 8. In other words, the double gripping edge prevents the button from tilting, when moved into the opening 9.

The construction of the button 11 is also of advantage in securing the button to the plate or object 7. Thus, the aperture 16 can be used for receiving a tapered pin or other member to center the button on the plate 7, with the plate 7 laid face down on a table or other support and the button resting on the back of said plate 7. Furthermore, the aperture 16 can be used for dropping solder therethrough onto the plate 7 to run from the center to the portion 17 and between said portion 17 and plate 7, thereby conveniently soldering the button to the plate 7. The annular attaching portion 17 is of advantage in order to distribute the contacting surfaces of the button and name plate in such a way as to reduce to a minimum the possibility of the enamel or finishing on the name plate being cracked when pushing the name plate into place.

Having thus described the invention, what is claimed as new is:

1. The combination with an object to bear against another object beyond the edge of an opening in the secondnamed object, of two resilient members carried by the firstnamed object and arranged to move in succession into said opening and to frictionally engage the wall of the opening, each of said

members being adapted to be sprung when entering the opening to grip the wall of the opening with a binding action, the member which enters the opening first being rotatable with reference to the firstnamed object 70 and the other member being non-rotatable with reference to said object.

2. The combination with an object to bear against another object beyond the edge of an opening in the secondnamed object, of 75 resilient gripping members carried by the firstnamed object to enter the opening in succession and frictionally engage the wall of the opening, said members being adapted to be sprung when entering the opening to 80 grip the wall of the opening with a binding action, and the member which enters said opening first being more freely resilient than the other member.

3. The combination with an object to bear against another object beyond the edge of an opening in the secondnamed object, of 85 resilient gripping members carried by the firstnamed object to enter the opening in succession and frictionally engage the wall 90 of the opening, said members being adapted to be sprung when entering the opening to grip the wall of the opening with a binding action, the member which enters said opening first being rotatable with reference to the firstnamed object and being more freely 95 resilient than the other member, and said other member being non-rotatable with reference to the first named object.

4. The combination with an object to bear 100 against another object beyond the edge of an opening in the secondnamed object, of two disks, one secured to the firstnamed object and having a central offset portion providing an abutment to which the other disk is secured, said disks being adapted to enter 105 said opening with their edges frictionally engaging the wall of the opening, and each disk being adapted to be sprung when entering the opening to grip the wall of the opening with a binding action.

5. The combination with an object to bear 110 against another object beyond the edge of an opening in the secondnamed object, of two resilient disks, one disk being secured to the firstnamed object and having a central offset portion providing an abutment, the other disk having a swivel connection 115 with said abutment, the edges of the disks being engageable frictionally with the wall of the opening, and each disk being slightly larger than the opening to be sprung when entering the opening for gripping the wall 120 of the opening with a binding action.

6. The combination with an object to bear 125 against another object beyond the edge of an opening in the secondnamed object, of two resilient disks, one disk having an offset central portion, an attaching portion surrounding said portion secured to the first- 130

named object, and a resilient marginal flange surrounding the firstnamed portion, said flange and edge of the other disk being frictionally engageable with the wall of the 5 opening when entering the opening, the last-named disk being secured to the firstnamed portion, and the lastnamed disk and said flange being slightly larger than the opening 10 to be sprung when entering the opening so as to grip the wall of the opening with a binding action.

7. The combination with an object to bear against another object beyond the edge of an opening in the secondnamed object, of 15 two resilient disks, one having a central offset portion providing an abutment, an an-

nular attaching portion surrounding said portion and secured rigidly to the first-named object, and a marginal flange surrounding the firstnamed portion, the other 20 disk having a swivel connection with said abutment and being more freely resilient than the first named disk, said flange and lastnamed disk being concavo-convex and slightly larger than the opening to be 25 sprung when entering the opening so as to frictionally grip the wall of the opening with a binding action.

In testimony whereof I hereunto affix my signature.

DE WITT TALMADGE MOATS.
